UNITED STATES PATENT OFFICE.

RENÉ GEORGES LÉON DUSUZEAU, OF BILLANCOURT, FRANCE, ASSIGNOR TO SOCIÉTÉ DES MOTEURS SALMSON (Système CANTON-UNNE), OF BILLANCOURT, FRANCE.

MAGNETO.

1,356,975.

Specification of Letters Patent.

Patented Oct. 26, 1920.

Application filed April 24, 1917. Serial No. 164,157.

To all whom it may concern:

Be it known that I, RENÉ GEORGES LÉON DUSUZEAU, citizen of the Republic of France, residing at 9 Avenue des Moulineaux, Billancourt, Seine, in the Republic of France, have invented new and useful Improvements in Magneto's, of which the following is a specification.

This invention consists in a peculiar construction of magneto of the type comprising a rotating inductor member, which is characterized essentially by the arrangement and construction of the armature, this latter having the shape of a U between the limbs of which the said inductor member is arranged to rotate.

A practical constructional form of a magneto with a rotating inductor member according to this invention, is illustrated by way of example in the accompanying drawings in which:

Figure 1 is a longitudinal section of the improved magneto, and

Fig. 2 is a cross section thereof on the line X—X of Fig. 1.

As shown, the improved magneto comprises essentially an armature B of U-shape whose primary and secondary windings are situated at D between the limbs b of the U.

An inductor member composed of two soft iron pieces E mounted on a non-magnetic core C integral with the driving cone spindle is adapted to rotate in the circular cavity or bore inclosed by the two limbs b of the armature and the intermediate pole pieces M.

The armature B is let into the frame A in which the pole pieces M are inserted and are surmounted by the magnets a. The armature B is fixed to the said frame by means of screws V.

This arrangement provides a magneto which is very easy to manufacture owing to the simple forms of the armature and inductor.

If the magnetic flux passing through the armature core in the downward direction be considered as being positive (+), and the flux passing through the armature core in the upward direction be considered as being negative (-), then the following table

will indicate the action of the soft iron inductor during a revolution of the latter through 360 degrees:—

Angles of rotation	0°	90°	180°	270°	360°
Variations of the flux	0	+	0	-	0

It will therefore be perceived that during a complete revolution of the inductor, the flux attains four absolute maximum values. The improved apparatus thus produces four sparks during every revolution.

Having now described my invention, what I claim as new and desire to secure by Letters Patent is:

1. A magneto comprising in combination: a U shaped magnet, pole pieces secured to the branches of said magnet at the ends of a diameter passing through a central axis, a U shaped armature, the limbs of which are located at the ends of a diameter at right angles with the first mentioned diameter, a non-magnetic spacing member arranged coaxially with the said axis, two diametrically opposed inductor members secured to said spacing member, armature limbs having a length substantially equal to the length of the inductor members plus the depth of the winding and the ends of the limbs being in alignment with the outer ends of said inductor members, a rotary shaft to which the outer end of said spacing member is secured and bearing means located beyond the outer end only of the spacing member and in which the rotary shaft is rotatably supported.

2. A magneto comprising in combination: a U shaped magnet, pole pieces secured to the branches of said magnet at the ends of a diameter passing through a central axis, a U shaped armature, the limbs of which are located at the ends of a diameter at right angles with the first mentioned diameter, a non-magnetic spacing member arranged coaxially with the said axis, two diametrically opposed inductor members secured to said spacing member, the armature limbs having a length substantially equal to the length of the inductor members plus the depth of the winding and the ends of the limbs being

in alinement with the outer end of said inductor members, a rotary shaft to which the outer end of said spacing member is secured and bearing means located beyond the 5 outer end only of the spacing member and in which the rotary shaft is rotatably supported.

In testimony whereof I have signed my name to this specification in the presence of two subscribing witnesses.

RENÉ GEORGES LÉON DUSUZEAU.

Witnesses:

LOUIS MOSES,
CHAS. P. PRESSLY.
